AUTOMOBILE AIR CONDITIONING CASE

William E. Lind, 1401 Foch St., Fort Worth, Tex.

Filed Dec. 5, 1960, Ser. No. 63,108

Term of patent 3½ years

(Cl. D14—6)

FIG. 1.

FIG. 2.

FIG. 3.

FIG. 4.

FIG. 5.

FIGURE 1 is a top plan view of an automobile air conditioning case showing my new design;

FIGURE 2 is a front elevational view;

FIGURE 3 is a side elevational view;

FIGURE 4 is an enlarged broken sectional view taken on line 4—4 of FIGURE 2; and

FIGURE 5 is a bottom plan view of the forward portion of the case.

I claim:

The ornamental design for an automobile air conditioning case, substantially as shown.
